(57) **CLAIM**

The ornamental design for a bandages pouch, as shown and described.

DESCRIPTION

FIG. 1 is an isometric view of a pouch for bandages showing our new design;

FIG. 2 is a top plan view of the pouch for bandages;

FIG. 3 is a bottom plan view of the pouch for bandages;

FIG. 4 is a first end elevational view of the pouch for bandages;

FIG. 5 is a second end elevational view of the pouch for bandages; and,

FIG. 6 is a side elevational view, the opposite side elevational view thereof being the same.

The broken line showing of environment in the drawings is for illustrative purposes only and forms no part of the claimed design.
